UNITED STATES PATENT OFFICE.

KENNETH L. EDDY, OF CHICAGO, ILLINOIS, ASSIGNEE, BY MESNE ASSIGNMENTS, TO AUTOMATIC UTILITIES COMPANY, OF CHICAGO, ILLINOIS, A CORPORATION OF ILLINOIS.

LOOSE LEAF OR CARD INDEX DEVICE.

1,186,470.

Specification of Letters Patent. Patented June 6, 1916.

Application filed May 17, 1915. Serial No. 28,518.

To all whom it may concern:

Be it known that I, KENNETH L. EDDY, a citizen of the United States, and a resident of Chicago, in the county of Cook and State 5 of Illinois, have invented certain new and useful Improvements in Loose Leaf or Card Index Devices; and I do hereby declare that the following is a full, clear, and exact description thereof, reference being had to the 10 accompanying drawings, and to the letters of reference marked thereon, which form a part of this specification.

This invention relates to improvements in loose leaf or card index devices and consists 15 of the matters hereinafter described and more particularly pointed out in the appended claims.

The invention relates to a loose leaf or card index device which comprises a cabinet 20 having an index card or plate fixed to the outer face of one side or end, a plurality of loose leaves or cards having corresponding indexes supported in the cabinet in planes parallel to the said side or end, and an operating device which is movable with respect 25 to the cabinet index card. Said operating device is adapted to coact with index clips attached to the loose leaves or cards in such a way that it constitutes a finder or selector 30 and by its operation acts to segregate all cards corresponding to a certain index character, whatever their location in the cabinet may be.

The index card on the cabinet may be 35 provided with one or more sets of index characters and the cards are likewise provided with the same sets of characters. In the example illustrated herein, the cabinet index card and likewise the cards themselves are provided with two sets of index characters, namely, an alphabetical set and a numerical set. Thus the subject matter on the cards may be indexed, both alphabetically and numerically, and the numbers may 40 be used to indicate subject matter so that the numerical index will constitute a subject matter index.

Other kinds of indexes may be provided and if desired, the cabinet may be built to 45 provide more than two sets of indexes.

In the embodiment of the invention illustrated herein, the index clips are attached at the bottom margins of the cards, and the

operating device or finder includes a frame which is expandible vertically, so that upon 55 the proper manipulation of an operating arm that projects out of the cabinet, said frame will act to raise the cards corresponding to the desired index character above the other cards. This expanding frame is 60 mounted on a carriage extending longitudinally of the cabinet beneath the cards and is movable transversely of the cabinet. Said carriage rides on tracks or rails fixed within 65 the cabinet.

The object of the present invention is addressed more particularly to improvements in the operating device or finder to the end of improving its operation and of making its action more accurate and certain and also 70 for the purpose of cheapening and economizing the cost of manufacturing the same. This and other objects and advantages of my invention will appear more clearly as I proceed with my specification.

In the drawings:—Figure 1 is a perspective view of my improved card index cabinet. Fig. 2 is a view representing a front elevation of the same. Fig. 3 is a perspective view of one of the cards used 80 in the index cabinet. Fig. 4 is a top plan view of the cabinet with the top removed. Fig. 5 is a view representing a transverse vertical section through the cabinet in a plane indicated by the line 5—5 of 85 Fig. 4. Fig. 6 is a view representing a longitudinal vertical section through the cabinet in a plane indicated by the line 6—6 of Fig. 5. Fig. 7 is a sectional view similar to Fig. 6 with the parts shown in a different 90 relation. Fig. 8 is a perspective view of the carriage used in the cabinet, said carriage being shown on fragments of the tracks on which it rides. Figs. 9 and 10 are views representing vertical sections through one of the bearing blocks of the carriage, said sections being indicated by the lines 9—9 and 10—10 respectively in Fig. 5. Fig. 11 is a detail perspective view on an enlarged scale of one of the clips applied to the bottom edges of the cards. Fig. 12 is a view representing in perspective the front plate on the cabinet as said plate appears when looking at the same from the rear.

Referring now to that embodiment of my 105 invention illustrated in the drawings:—20

indicates the cabinet, which contains the loose index leaves or cards and the operating device or finder for segregating all leaves or cards corresponding to any certain index character from the rest of the leaves or cards in the cabinet. The cabinet consists of an oblong box 21, open at the top and having side walls 22, 22, rear end wall 23, front end wall 24 and a bottom wall 25.

10 A removable cover 26 is preferably provided to close the cabinet and keep out dust.

On the front end wall 24 of the cabinet is fixed an index plate 27. As above stated, this index plate as illustrated herein, is constructed to provide two sets of index characters, namely, a set of alphabetical characters and a set of numerical characters. Thus the cards or leaves may be indexed both alphabetically and numerically or according to either of said indexes alone.

28 indicates the alphabetical index, and 29, the numerical index. The numerical index may be made to accord with certain heads or subjects, with each numeral indicating a particular head or subject.

The characters of each index are arranged in a horizontal line extending transversely of the plate 27, and are accurately spaced in said line to correspond with the spacing 30 of teeth 30 placed at the top and bottom edges of a horizontal slot 31 in the plate 27. Through this slot projects an operating arm 32, having a handle or knob 33 for ease in grasping it, which arm, as will be shown 35 later, is connected to an expanding frame mounted on the carriage within the cabinet. A second slot 34 is formed in the plate 27 between the two lines of index characters 28, 29 and through this slot projects a rod 40 carrying a pointer 35, which is movable transversely of the cabinet with the carriage and with the arm 32. This pointer is double headed, each head being associated with one of the sets of index characters. As shown, 45 the spaces containing the characters of the two sets of index characters are arranged in staggered relation, each character of one set being located vertically below (or above) a point half way between two adjacent characters of the other index and the teeth 30 in the edges of the slot 31 are spaced apart at distances equal to half the distances at which the characters of the two indexes are spaced. This arrangement provides for a 50 maximum of longitudinal space for the index characters, with a minimum of lengths of space for said characters, and also provides for a maximum total number of index characters.

60 36 indicates as a whole the carriage, upon which is mounted the expandable frame that constitutes part of the operating mechanism. Said carriage is mounted to ride on tracks or rails 37, 38, spaced respectively adjacent 65 to the front and rear end walls of the cabi-

net and fixed transversely on the bottom wall thereof.

39, 40 indicate the end frame members or end blocks of the carriage. Each of said blocks is of the same construction so that 70 a description of one will suffice for both. Each block has a longitudinally extending groove 41 at the bottom which groove is rectangular in cross section and is made to embrace the associated track 37 (38) which 75 engages within it. One side of the groove is formed by a flat vertical flange 43 which engages against the flat inner face 43^a of the associated rail. The opposite side of said groove is also formed by a flat vertical 80 flange 44, but the flange in this case has a longitudinally extending horizontal shoulder 45 at its bottom end which has bearing within a longitudinally extending groove 45^a in the outer vertical face of the associated track. The said shoulder and groove provide the supporting bearing for the end frame of the carriage member on the associated rail. The top wall of the groove 41 having no bearing whatever on the top of 90 the said rail. At the top of the rail are provided rack teeth 46 which are engaged by a pinion 47 (see Fig. 9) keyed to the end of a shaft 48 that extends longitudinally of the carriage and that has bearing in the two 95 end frame members or blocks. The blocks are recessed above the groove 41 to receive the pinion 47. A rod 49 spaced laterally from the shaft 48 constitutes the means for rigidly connecting the end frame members or blocks of the carriage together. Said rod is riveted at its outer ends against the outer faces of the frame blocks and holds the shoulders on said blocks in proper position relative to their respective tracks or 100 rails.

It is to be understood that the bearing for the carriage on the rails is provided entirely by the shoulders 45 and the grooves 45^a in the outer faces of the rails within 110 which said shoulders engage, and that the pinions 47 have no bearing upon the racks with which they are engaged but are merely effective so far as the horizontal position of the carriage on the tracks is concerned.

115 It will be manifest from the construction described that when the front end frame or block of the carriage is moved on its associated rail, its movement will cause a rotative movement to be imparted to the shaft 48 by reason of the engagement of the rack teeth 46 with the pinion 47, at the front end of said shaft. This movement will be communicated to the pinion 47 at the rear end of said shaft and said pinion, by its engagement with the rack on the rear rail or track, will produce a movement of the rear end block or frame member 40 on its rail 38 corresponding exactly to the movement of the front end frame member. By reason of 120 125 130

this construction, the slightest lateral movement of the front end of the carriage will be communicated in exactly like amount in either direction to the rear end of said carriage.

Such exact coaction between the front and rear ends of the carriage is essential in this type of apparatus, since the true alignment of the expansion frame is required in order 10 that the finder may simultaneously and with the same movement engage the index clips of all the cards bearing said clips in the same position on said cards.

The construction described absolutely prevents not only any distortion between the front and rear end frame members of the carriage but also eliminates any tendency for either of the two end frame members to bind against their respective rails.

20 On the carriage is mounted the expansion frame 50, which has been hereinbefore referred to and which is adapted to raise above and thus segregate from the other loose leaves or cards in the cabinet those 25 corresponding to the index character in line with which said expansion frame is brought. Said frame comprises a top bar 51, a bottom bar 52, and two link connections formed by bars 53, 53, connected respectively to said top and bottom bars near their front ends in the manner of a parallel expansion rule. Vertical slots 54, 54, are formed in the opposite faces of the end frame blocks 39, 40, and the top bar 51 of 35 the aforesaid expansion frame engages within said slots in such manner as to be capable of a vertical movement only. The ends of said bar 51 engage against the end wall 54^a of said slots. The bottom bar 52 is located in the plane of said slots but is incapable of vertical movement, projecting at its forward end through a hole or opening 55 in the front block and having bearing 40 at its rear end in a hole or opening 56 through which it is adapted to extend when pushed home as presently to be described. The forward projecting end of the bottom bar 52 constitutes the operating arm 32 above referred to.

50 When the operating arm 32 is pushed inwardly with respect to the cabinet, that is to say, in such manner as to push the bottom bar 52 of the expanding frame longitudinally toward the rear of the cabinet, it will be manifest that, as the top bar 51 is incapable of longitudinal movement, it will be raised by the links 53. A shoulder 32^a is formed on the operating arm 32 at a point in advance of the front frame block 60 and this shoulder is adapted to strike the front face of said block and thus limit the rearward movement of the bottom operating bar of the expanding frame and stop further movement of the top bar 51. The 65 operating member is normally held in its

outermost position by means of a tension spring 57 placed at one side of the expansion frame and arranged to connect the bottom bar 52 with the front block 39.

Top and bottom transverse notches 32^b 70 are formed in the operating arm 32 in such position that when the operating arm is at its outermost position, said notches will be located in the plane of the rack teeth 30 in the slot 31 of the cabinet index plate. Forward of these notches the operating arm is provided at the top and bottom with longitudinally extending V-shaped edges 32^c 75 which are adapted to engage the teeth 30. The pointer 35 is mounted on a rod 35^a fixed 80 to and extending forwardly from the front end frame block 39 of the carriage.

It is manifest from the foregoing description that with the parts of the expandible frame in their normal position and with the 85 operating arm 32 in its outermost position, the carriage 50 may be moved transversely of the cabinet in either direction by means of the handle 33 so as to bring the pointer 35 opposite any one of the index characters 90 of either of the indexes on the index plate. If the operating arm 32 be then pushed inwardly, the top and bottom V-shaped edges 32^c on said arm will engage the teeth 31 in the slot 30 and properly center the 95 carriage in a position corresponding to the center position of said index character and also lock the carriage in that position. The inward movement of the operating arm also, as has been pointed out, raises the top bar 100 51 of the expansion frame on the carriage to a level where it will engage such index clips on the bottoms of the cards as correspond in their position on said cards to the 105 position of the index character on the index plate of the cabinet.

61 indicates the loose leaves or cards of the device and 60 the index tabs or clips applied to the bottom edges thereof. The said cards are ruled and printed along their bottom marginal parts to provide sets of index characters 28^b, 29^b corresponding respectively both in kind and in position to the sets of index characters on the cabinet index plate. The clips are adapted to be attached 110 to the cards in positions opposite any one of the characters on the cards and may be made of any suitable construction making them capable of easy attachment. As shown and as they are preferably made, each clip 115 consists of a short narrow plate of thin metal slightly wider at its upper end and punched to provide an opening 60^a to disclose the index character to which it is to be applied, the punched out part 60^b being bent 120 out of the plane of the front part to provide a member for engagement with the rear side of the card. The clip is notched at its lower end for engagement with the top bar 51 of 125 the expansion frame on the carriage. As 130

many clips may be applied to each index card as there are kinds of indexes. For example, in the present case an index clip may be applied to each card corresponding to the letter under which the subject matter on the card is indexed alphabetically, and a second clip may be applied in a position corresponding to the number which indicates the subject matter under which said card is to be indexed.

Manifestly when the operating bar is brought to a certain position corresponding to any of the index characters on the index plate of the cabinet and is pushed inwardly, the top bar 51 of the expansion frame will be raised and will engage the clips on the cards and thus elevate all the cards having clips in like locations above the other cards in the cabinet.

20 The cards are preferably reinforced by metal strips 62, which are bent about the end edges of the cards so as to embrace opposite faces thereof. These strips when made in this way not only act to reinforce said edges, but also act to properly space the cards so that when a card is inserted between two others, the index clip or clips at the bottom margin of the cards will not engage against the clips of adjacent cards and thus obstruct the insertion of said cards. Said strips also act to properly space the cards at their upper edges and offset the effect of the thickness of the clips located at the bottom edges of the cards. The cards 35 are supported in the cabinet by longitudinally extending bars or strips 63 which, as shown, are fixed to the side walls of the cabinet. Said bars support the cards in a position such that the index clips are vertically removable from the top bar 51 of the expansion frame 50 in the ordinary position of the parts.

While in describing my invention I have referred to certain details of mechanical construction and arrangement, it is to be understood that the invention is to be in no way limited thereto except as pointed out in the appended claims.

I claim as my invention:—

50 1. In a card index device of the kind described, in combination with the cabinet, and the cards supported therein, a carriage movable transversely of the cabinet, said carriage including a vertical expandable frame, and an operating arm for expanding said frame, said carriage including end blocks spaced near the front and rear ends of the cabinet, tracks fixed transversely in said cabinet on which said blocks have bearing, and means connecting said end blocks with each other and with said tracks, whereby the slightest movement of the front end block transversely of the cabinet in either direction is communicated to the rear end 65 block thereof.

2. In a card index device of the kind described, in combination with the cabinet, and the cards supported therein, a carriage movable transversely of the cabinet, said carriage including a vertical expandable frame, and an operating arm for expanding said frame, said carriage including end blocks, rails extending transversely of said cabinet, interengaging parts providing bearing of said end blocks on said rails, each rail being provided with a rack, a shaft extending longitudinally of the carriage and having bearing in said end blocks, and pinions, one for each end block, fixed to said shaft and engaged with said racks, said pinions providing no bearing for said end blocks.

3. In a card index device of the kind described, in combination with the cabinet, and the cards supported therein, a carriage movable transversely of the cabinet, said carriage including a vertical expandable frame, and an operating arm for expanding said frame, said carriage including end blocks, tracks provided with racks fixed transversely in said cabinet, a shaft extending longitudinally of said carriage rotatively mounted in said end blocks, pinions, one for each end block, fixed to said shaft and engaged with said rack but providing no bearing for said end blocks, and means providing sliding bearing for said end blocks on said tracks in a plane below the plane of said racks.

4. In a card index device of the kind described, in combination with the cabinet, and the cards supported therein, a carriage movable transversely of the cabinet, said carriage including a vertical expandable frame, and an operating arm for expanding said frame, said carriage including end blocks, tracks provided with racks fixed transversely in said cabinet, a shaft extending longitudinally of said carriage rotatively mounted in said end blocks, pinions, one for each end block, fixed to said shaft and engaged with said rack but providing no bearing for said end blocks, and means providing sliding bearing for said end blocks on said tracks, said means being constructed to prevent vertical displacement of said end blocks.

5. In a card index device of the kind described, in combination with the cabinet, and the cards supported therein, a carriage movable transversely of the cabinet, said carriage including a vertical expandable frame, and an operating arm for expanding said frame, said carriage including end blocks, rails fixed in said cabinet and extending transversely thereof, said rails being provided with longitudinally extending grooves located below their top edges and with racks at their top edges, said blocks being provided with shoulders that provide the sole bearing engagement for said end blocks.

blocks on said rails, a shaft extending longitudinally of said carriage and having bearing in said end blocks, and pinions, one for each end block, fixed to said shaft and engaged with said racks.

6. In a card index device of the kind described, in combination with the cabinet, and the cards supported therein, a carriage movable transversely of the cabinet, said carriage including a vertical expandible frame, and an operating arm for expanding said frame, an index plate on said cabinet provided with a slot through which said operating arm projects, said index plate having one or more sets of index characters arranged in spaced relation parallel to said slot, an index head movable with said frame over said index plate, said slot being provided with teeth graduated to correspond with the spacing of said index characters, said operating arm being provided with a longitudinally extending edge adapted for engagement with the teeth in said slot for centering and locking said arm when it is brought into a position corresponding with the position of any index character.

7. In a card index device of the kind described, in combination with the cabinet, and the cards supported therein, a carriage movable transversely of the cabinet, said carriage including a vertical expandible frame, and an operating arm for expanding said frame, an index plate on said cabinet provided with a slot through which said operating arm projects, said index plate having one or more sets of index characters arranged in spaced relation parallel to said slot, an index head movable with said frame over said index plate, said slot being provided with teeth graduated to correspond with the spacing of said index characters, said operating arm being provided with a longitudinally extending edge adapted for engagement with the teeth in said slot for centering and locking said arm when it is brought into a position corresponding with the position of any index character, and an index clip adapted for attachment to said cards, each of said index clips being notched at their

bottom ends for engagement with the rising member of said expansion frame.

8. In a card index device of the kind described, in combination with a cabinet provided with an index plate on its exterior, a plurality of cards located within said cabinet, an operating device located within said cabinet and having an arm projecting without said cabinet and associated with the cabinet index plate, said operating device comprising a carriage consisting of end blocks, means rigidly connecting said end blocks, a vertically expandible frame supported in said end blocks and being capable of transverse movement with the carriage in said cabinet, said expandible frame including a bar capable of vertical movement in said blocks but being incapable of endwise movement, a second bar capable of endwise movement but incapable of vertical movement and links connecting said bars.

9. In a card index device of the kind described, in combination with a cabinet having an index plate, a plurality of cards located within said cabinet and having corresponding indexes, an operating device located within said cabinet and having an arm projecting without said cabinet and associated with the cabinet index plate, said operating device comprising a carriage consisting of end blocks, means rigidly connecting said end blocks, a vertically expandible frame supported in said end blocks, rails fixed in said cabinet, means providing sliding bearing of said blocks on said rails, a shaft having bearing in said blocks, pinions fixed to said shaft in the neighborhood of each block, and racks on said tracks engaged by said pinions but providing no bearing between said carriage and said tracks.

In testimony, that I claim the foregoing as my invention I affix my signature in the presence of two witnesses, this 11th day of May, A. D. 1915.

KENNETH L. EDDY.
